Pannie, Davis, Marvin & Edmonds.

UNITED STATES PATENT OFFICE.

LOUIS ADLMAN, OF NEW YORK, N. Y., ASSIGNOR TO PIONEER BRAID MANUFACTURING CO., INC., OF NEW YORK, N. Y., A CORPORATION OF NEW YORK.

DESIGN FOR BRAID.

59,532.

Specification for Design.

Patented Nov. 1, 1921.

Application filed July 16, 1921. Serial No. 485,304. Term of patent 14 years.

To all whom it may concern:

Be it known that I, LOUIS ADLMAN, a citizen of the United States, residing at New York city, in the county of New York and State of New York, have invented a new, original, and ornamental Design for Braid, of which the following is a specification, reference being had to the accompanying drawing, forming part thereof.

The figure is a plan view of the braid, showing my new design.

I claim:

The ornamental design for braid as shown.

LOUIS ADLMAN.

Witnesses:

SAMUEL SIEGEL,
W. H. ROBINSON.
